UNITED STATES PATENT OFFICE.

ERIC VILHELM LARSON AND HUGO LINDEBERG, OF ESKILSTUNA, SWEDEN, ASSIGNEES
TO ESKILSTUNA SEPARATOR AKTIEBOLAG, OF ESKILSTUNA, SWEDEN, A SWEDISH
COMPANY.

SEPARATOR BOWL.

Application filed July 16, 1924. Serial No. 726,250.

To all whom it may concern:

Be it known that we, ERIC VILHELM LARSON and HUGO LINDEBERG, subjects of the King of Sweden, and residents of Eskilstuna, Sweden, have invented a new and useful Improvement in Separator Bowls (for which an application for patent has been filed in Sweden, March 5, 1923), of which the following is a specification.

10 The present invention relates to an improvement in separator bowls of the type which are provided with liner plates placed on and surrounding a central spider or a central distributing sleeve, and with a so-called upper plate placed on top of said liner plates and which serves as a partition between the separated liquids, i. e. the cream and the skimmed milk, and which also prevents the liner plates located underneath 15 the same from becoming deformed at the rapid rotation of the bowl. Said upper plate must have such shape that it provides space for the upper ends of the milk distributing channels provided on the central spider, or 20 on the central sleeve, and which serve to distribute the admitted whole milk into the bowl. For this purpose it is usual to provide the neck of said upper plate with an enlargement. Said enlargement, however, 25 has been found to cause a less efficient skimming which according to investigations made appear to be due to whirls or eddies arising in the enlargement which disturb the even flow of the cream.

30 The purpose of the improvement forming the subject of the present invention is primarily to avoid the said difficulty. For this purpose the improvement consists broadly in that in the portion of the said 35 enlargement of the neck of the upper plate which is not occupied by the upper end or ends of the milk distributing channel or channels there is provided a ring which largely fills up the said enlargement in such 40 manner that the lower faces of the upper plate and of the ring obtain together as nearly as possible the same shape as the liner plates, so that in this manner there is formed a passage of approximately uniform width 45 for the cream along the lower side of the upper plate. In this manner eddies in the cream are prevented so that a superior skimming is obtained.

50 In the accompanying drawing an embodiment of the invention is illustrated by way

of example. Fig. 1 shows a vertical section of a separator bowl according to the invention, Fig. 2 shows a horizontal section through the upper portion of the bowl on the line II-II in Fig. 1, Fig. 3 shows a vertical section of a separator bowl according to a modification of the invention, and Fig. 4 shows a horizontal section through the upper portion of the bowl on the line IV-IV in Fig. 3.

55 Around the tubular standard or central feed tube 1 of the separator bowl a distributing sleeve 2 is placed which may be guided on the tube, for instance by means of a button 3. In the embodiment illustrated the 60 sleeve 2 is provided with three hollow projections 4 pressed out in the same and which form milk distributing channels 5 between said sleeve and said tube 1, said channels serving to receive whole milk from the interior of the tube 1 through apertures 6 in the wall of the same, and to conduct said milk and distribute the same in the bowl. Said projections 4 serve at the same time as 65 guiding ribs for guiding the conical liner plates 7 which are run onto said sleeve, said plates being for this purpose provided with central holes of a corresponding shape. The upper plate 8 rests on top of the liner plates 70 and forms a partition between the cream, 75 which flows out along the inner or lower face of said upper plate, and the skimmed milk, 80 which flows out above said upper plate. Said upper plate 8 also serves to prevent 85 deformation of the liner plates at the rapid rotation of the bowl. In order to provide 90 space for the upper ends of the projections 4 which form the milk distributing channels 5, the neck 9 of the upper plate 8 is provided with an enlargement 10. According to 95 the present invention there is secured in the enlargement 10 a solid ring 11 which fills up the greater portion of the enlargement. The lower surface of ring 11 co-operates with 100 the lower surface of plate 8 to form a face substantially conforming in shape to the upper face of the liner plates 7, and said lower face is at all points at practically the same small distance from the upper liner plate 7. By this means the formation of whirls or 105 eddies in the cream is prevented when the cream flows upwards along the inner or lower face of the upper plate 8, and a superior skimming effect is therefore obtained. 110 Conditions will be the same if instead of the

detachable distributing sleeve 2 a so-called central spider is used, that is to say if the central feed tube 1 is provided with longitudinal ribs, in which case the whole milk 5 may be conducted through slots or passageways in said ribs.

In order that also the upper plate 8 shall be guided on the sleeve 2 a recess 12 is provided in the ring 11, said recess being engaged by one of the projections 4 which projects a slight distance beyond the two other projections in the radial direction. By this means the upper plate 8 will thus be guided in the same manner as the liner 15 plates 7. It will be understood that the ring 11 may be provided for the same purpose with several such recesses 12, for instance one recess for each projection 4.

The purpose of the present invention may 20 of course also be attained by making the upper plate 8, instead of providing it with a circumferential enlargement, of such shape that it follows the lower and inner faces of the ring 11, that is to say by merely providing the upper plate with one or more vertical recesses fitting one or more of the projections forming the milk distributing 25 chambers.

Figs. 3 and 4 illustrate this modification. 30 In this construction the central feed tube 1, distributing sleeve 2, button 3, hollow projections 4, milk distributing channels 5, apertures 6 and conical liner plates 7 are similar to those above described in connection with the construction according to Figs. 35 1 and 2. An upper plate 18 rests on the liner plates and has the same functions as the upper plate 8 in Figs. 1 and 2. Said upper plate is provided with a neck 19, but 40 instead of said neck being provided with an enlargement as in the embodiment above described, said neck is joined to the conical upper plate 18 by the annular substantially flat portion 20, so that the lower face of the 45 upper plate, comprising the lower surfaces of portions 18 and 20, obtains a shape substantially conforming to the upper face of the liner plate, as will be seen by reference to Fig. 3. In order to provide space for the 50 upper ends of the projections 4, recesses 21 are formed at the bend between the plate 18 and the neck 19, i. e. at the lower end of said

neck 19 and in the portion 20, said recesses being formed by pressing out the sheet metal of the plate and neck. Said recesses 55 conform in shape to the upper ends of the projections 4 one of which is preferably made larger than the other, as shown in Fig. 4, in order to provide a simple means for properly lining up the plates on the distributing sleeve 2.

We claim:

1. In a separator bowl the combination of a central feed tube, projections on said tube, liner plates surrounding said tube, an upper 65 plate on top of said liner plates and surrounding said tube, said upper plate having a lower face substantially conforming in shape to the upper face of said liner plates, and said upper plate being provided with 70 recesses for receiving the upper ends of said projections.

2. In a separator bowl the combination of a central feed tube, projections on said tube, liner plates surrounding said tube, an upper 75 plate on top of said liner plates and surrounding said tube, said upper plate having an enlargement providing space for the upper ends of said projections, and a ring attached to said upper plate and largely 80 filling up the portion of said enlargement unoccupied by said upper ends of said projections, the lower faces of said upper plate and said ring conforming substantially in shape to the upper face of an adjacent liner 85 plate.

3. In a separator bowl the combination of a central feed tube, projections on said tube, liner plates surrounding said tube, an upper 90 plate on top of said liner plates and surrounding said tube, said upper plate having an enlargement providing space for the upper ends of said projections, and a ring attached to said upper plate and largely 95 filling up the portion of said enlargement unoccupied by said upper ends of said projections, said ring being provided with a recess adapted to be engaged by the upper end of one of said projections, and the lower faces of said upper plate and said ring conforming substantially in shape to the upper 100 face of an adjacent liner plate.

ERIC VILHELM LARSON.
HUGO LINDEBERG.
